UNITED STATES PATENT OFFICE

CHARLES B. McDONALD, OF DETROIT, MICHIGAN, ASSIGNOR TO WILCOX PRODUCTS CORPORATION, OF DETROIT, MICHIGAN, A CORPORATION OF MICHIGAN

METHOD OF FORMING TAPPETS

Application filed July 2, 1928. Serial No. 289,887.

The invention relates to tappets used for operating the valves of internal combustion engines and consists in the novel method of forming the same as hereinafter set forth.

5 In the drawings;

Figure 1 is an elevation of the chilled cast blank from which the tappet is to be formed.

Figure 2 is a similar view of a modified construction.

10 Figures 3 and 4 show the completed tappets corresponding respectively to Figures 1 and 2.

Figure 5 is an end elevation of Figure 3.

In the manufacture of tappets it is desirable to obtain hardened surfaces for engaging the 15 cam and also the bearing in which the tappet reciprocates. It has also been found that chilled cast iron is a desirable material for forming such surfaces. However, it is also necessary to form a threaded socket for receiving the adjusting screws. Chilled cast iron is too hard to permit of machining and therefore it is usual to construct the tappet or the portion thereof in which the threaded socket is formed, of metal sufficiently soft for 20 machining.

It is the object of the invention to obtain a construction in which all of the wearing surfaces are formed of chilled cast iron but which at the same time is provided with a soft core 30 that may be bored and threaded for receiving the adjusting screw. To this end the invention consists in the process and product as hereinafter set forth.

As shown in Figure 1 A is a blank having 35 a portion B which corresponds to the form of the tappet together with a sprue portion C and a portion D intermediate portions B and C which is of smaller diameter. This blank is cast in a chill, the metal being fed 40 into the portion B from the sprue portion so as to compensate for shrinkage and to obtain the required density in the full length of the portion B. The chill will impart to the surface portions of the metal adjacent thereto 45 a great degree of hardness but the hardening

effect does not extend into the central core. If, however, the blank were only of a length equal to the finished tappet its end portions as well as its sides would be hardened and it would be impossible to drill or machine the 50 core. This difficulty I have avoided by providing the extended sprue portion together with the contracted portion D which permits of breaking off the sprue thereby exposing the soft core. Thus to finish the tappet it is 55 only necessary to drill and thread as indicated at E.

The construction shown in Figure 2 is the same as that shown in Figure 1 with the exception that an enlarged head F is formed to 60 constitute the cam follower. This head is integral with the cylindrical portion for engaging the bearing, and a groove G is preferably formed between these portions to facilitate the grinding of the cylinder.

65 What I claim as my invention is:

1. The method of forming tappets which consists in casting a chilled blank of a length greater than the finished tappet, severing a portion of said length to expose the end of the 70 soft core and in then machining a socket in said core.

2. The method of forming tappets which consists in casting a chilled blank of greater length than the finished tappet provided 75 with a sprue portion for supplying the metal compensating for shrinkage, in severing said sprue portion to expose the end of a soft core in the remaining portion and in machining said core to form a socket therein.

80 3. The method of forming tappets which consists in casting a chilled blank of a length greater than that of the finished tappet, the extra length forming a sprue portion and a contracted portion intermediate said sprue portion and the tappet proper, in severing the blank in the plane of said contracted portion to expose the end of a soft core and in machining to form a socket in said core.

85 4. The method of forming tappets which 90

consists in casting a chilled blank with a soft core, exposing the soft core at one end of the blank, and in then machining a socket in said core.

5. The method of forming a tappet which consists in casting a chilled blank with a soft core, cutting the said blank to expose the soft core at one end of the blank, and in then forming a socket in said core through the exposed portion thereof.

10 In testimony whereof I affix my signature.
CHARLES B. McDONALD.
